UNITED STATES PATENT OFFICE.

BURT A. PETERSON, OF ROCKFORD, ILLINOIS, ASSIGNOR, BY MESNE ASSIGNMENTS,
TO EDGAR S. NETHERCUT, OF EVANSTON, ILLINOIS.

WINDER.

Application filed December 4, 1919. Serial No. 342,381.

To all whom it may concern:

Be it known that I, BURT A. PETERSON, a citizen of the United States, residing at Rockford, in the county of Winnebago and 5 State of Illinois, have invented certain new and useful Improvements in Winders, of which the following is a specification.

This invention relates to winders of the general type disclosed in Patent No. 1,267,977, dated May 28, 1918, to Howard D. Colman, wherein a winder-tending mechanism is adapted to travel around the winder and operate upon a plurality of winding units. The traveling mechanism shown in said 15 patent comprises means for measuring or gaging the yarn masses produced by the machine, means for preventing the yarn of a reserve supply bobbin from being tied to a full size yarn mass, and means for preventing the reserve bobbin from being transferred to running position. The object of 20 the present invention is to provide a comparatively simple mechanism of this general type which shall be adapted to cooperate 25 with a different type of supply bobbin-holder from that shown in said patent.

Referring to the accompanying drawings, Figure 1 is a front elevation of a portion of the winder-tending mechanism of a winder 30 embodying the features of my invention. Fig. 2 is a side elevation of the lower portion of the winder-tending mechanism showing the mechanism engaging with a bobbin-holder to actuate it, said bobbin holder being 35 shown in broken lines. Fig. 3 is a fragmentary vertical section taken transversely through the winder-tending mechanism. Fig. 4 is a fragmentary plan section through a portion of the winder-tending mechanism 40 taken in the plane of line 4-4 of Fig. 1. Fig. 5 is a similar view taken in the plane of line 5-5 of Fig. 1. Fig. 6 is a fragmentary front elevation of parts illustrated in Fig. 4 showing details of construction. Fig. 45 7 is an under side view of a portion of the winder-tending mechanism. Fig. 8 is a fragmentary elevation of the same. Fig. 9 is a perspective view of one of the parts. Fig. 10 is a rear side elevation of a portion 50 of the winder-tending mechanism.

The embodiment herein shown of the invention is generally similar to the machine disclosed in said Patent No. 1,267,977, and

consists of a plurality of winding units arranged side by side for unwinding yarn 55 from bobbins onto tubular cores to form cheeses, and a carriage 89 (Fig. 1) arranged to travel along the series of winding units, said carriage having mechanism for attaching the ends of the yarn on the bobbins to 60 the ends of the yarn on the cheeses, as well as for performing various other operations attending the production of cheeses.

Each winding unit comprises suitable bobbin-holding means. Herein I have indicated, by way of example, a bobbin-holder (BH, Fig. 2) of the type disclosed in my application Serial No. 323,194, filed September 11, 1919, to which application reference may be made for a full disclosure of 70 the bobbin-holder. It is sufficient to say here that the bobbin-holder comprises a reserve-bobbin pocket and a compartment to contain the bobbin being unwound. The spent bobbin is discharged from said compartment and the reserve bobbin transferred to said compartment by a skewer which is actuated by means including a plunger A (Fig. 2) arranged to be depressed by a cam bar on the winder-tending carriage. Said 80 plunger extends through a guide opening b which allows lateral movement of the plunger.

Each unit comprises a clamp (not shown) to hold the end of the thread of the reserve 85 bobbin. This clamp may, if desired, be similar to the one fully described in the before-mentioned patent.

Upon the winder-tending carriage is a suitable knot-tying mechanism (not shown) which may, for example, be similar to that shown in said Colman patent and so located as to be carried, in the travel of the winder-tending carriage, into operative relation to the reserve thread held by the clamp of each 95 winding unit.

Means is provided for detecting the fact that the cheese of any unit has reached the desired diameter. When such a cheese is reached by the winder-tending mechanism, 100 devices are actuated to prevent the reserve thread from entering the knot-tying mechanism, to prevent the reserve thread clamp from being opened, and to prevent the reserve bobbin from being transferred to the 105 unwinding compartment of the bobbin-

holder. The means for preventing the reserve thread from entering the knot-tying mechanism includes two arms 361 and 361^a, similar to those correspondingly numbered 5 in said Colman patent, which are actuated to deflect the reserve thread out of the path of the knot-tying mechanism as explained in the patent. For this purpose, the said arms are fixed upon a pivot 362, and rigidly 10 attached to said pivot is an arm 485 (Fig. 5) operatively connected with a lever 702 which is arranged to be swung, in a manner to be hereinafter described, whenever a yarn container or cheese attains a predetermined 15 size. The free end of the arm 485 is forked to receive a pin 487 that is carried by an arm 675 fixed to a rock shaft 676. Connected to said shaft is a device for preventing the plunger A from being operated. 20 The arm 361 carries a member 360 (Fig. 5) operable, as will hereinafter appear, to prevent the reserve clamp from being opened.

Referring now to Fig. 10: A bar 677 is fixed to the carriage 89 and extends longitudinally of the path of movement of said carriage. The lower edge of the bar is arranged to engage an anti-friction roller A' on the plunger A. At the leading end of the bar 677 is an inclined surface 678 which 25 depresses the plunger sufficiently to cause the spent bobbin to be doffed. Following the cam surface 678 is a dwell surface 679. On the lower edge of the bar 677 is a series 30 of cam surfaces 680, 681, 682, 683 and 684 adapted to actuate the plunger to place the reserve bobbin in running position immediately after the reserve thread has been tied to the exhausted thread. Extending along the bar 677, beside the cam surfaces 35 680—684, is a dwell surface 685 located at the same height as the dwell 679. Means is provided for switching the roller A' away from the cam surface 680 and onto the dwell 685 in case the cheese of that particular 40 unit is full. The switching means comprises a block 686 which is pivoted at one end to the bar 677 at 687. The bar 677 is cut away to form a recess 688 to receive the switch block 686. When the block is swung up into 45 said recess, the lower surface of the block is substantially flush with the dwell surfaces 679 and 685.

The dwell 685 is offset or at one side of the plane of the dwell 679, as best shown in 50 Fig. 7. In order to guide the plunger laterally from the dwell 679 to the dwell 685, there is inserted in the bar 677 a plate 689. The edge 690 of this plate is a continuation 55 of the incline 680. The side 691 of the plate 689 extends at an angle with reference to the dwells 679 and 685.

Gravity tends to hold the switch block 686 in such position that its lower surface forms a continuation of the surfaces 679 60 and 680, the switch block having a finger

692 which is arranged to engage a stop pin 693. Means is provided for locking the switch block in such position in order that it shall not yield to the upward pressure of the plunger A. The locking means consists 70 of a latch 694 pivoted to the bar 677 at 695 and notched to engage a lug 696 (Fig. 9) on the finger 692. Rigid with the latch 694 is a crank arm 697. A contractile spring 698 connected to said arm tends to move the 75 notched end of the latch into engagement with the lug 696. Connected to the arm 697 is a link 699 having an elongated opening 700 (Fig. 7) to receive a pin carried by a crank arm 701 (Fig. 2) on the rock shaft 676. 80

The means for rocking the shaft 676 to unlatch the switch block 686 and swing the thread-deflecting arms 361 and 361^a against the reserve thread comprises the lever 702 (Fig. 5) which is mounted on a pivot 703. 85 One arm of the lever 702 carries a pin 704 (Figs. 5 and 10) that lies in a hook 705 on an arm 485. The other arm of the lever 702 is normally held against a stop 706 by a contractile spring 707. Alined with the pivot 90 703 is a pivot 708 (Figs. 3 and 4) on which is mounted an arm 709. The lever 702 and the arm 709 are connected together by a bar 710. Preferably the lever 702, bar 710 and arm 709 are cast integrally to form a rigid 95 yoke member. Mounted on the pivot 708 is an arm 711 carrying a roller 712 that engages a cam 713 on a constantly rotating shaft 223. When the winder-tending mechanism reaches a full cheese, the arm 709 is 100 connected to the arm 711 so as to be moved by the cam 713 against the tension of the spring 707. The means for thus connecting the arms 709 and 711 comprises a latch 714 (Figs. 3, 4 and 6) pivoted at 715 on the 105 arm 709 and having a projection 716 adapted to enter a locking recess 717 in a plate 718 attached to the arm 711. At one side of the recess 717 is an inclined surface 719. A contractile spring 720 tends to swing the 110 latch into position for the projection 716 to enter the recess 717, and a stop lug 720^a on the arm 709 (Fig. 4) serves to limit movement of the latch member by the spring.

The means for preventing the projection 115 716 from entering the recess 717 until a full cheese is reached comprises an arm 721 (Figs. 3 and 6) arranged to engage a lug 714^a on the latch 714. The arm 721 is attached to a horizontal rock shaft 502^a. A 120 feeler or gage 505 is adjustably connected to said rock shaft by any suitable means, as, for example, that fully disclosed in Patent No. 1,267,977. The normal positions of the gage 505 and the arm 721 are determined by 125 contact of a projection 502^b on the shaft 502^a with a stop plate 502^c. The end 506 of the gage lies in the vertical plane occupied by the series of thrown-out cheeses and is arranged to engage and ride over a full cheese, 130

the normal position of the gage being adjustable to correspond with the size of the cheese desired.

When the gage 505 is in its normal position, the arm 721 lies in such position as to prevent the projection 716 from entering the recess 717 as the recess is moved under said projection by the cam 713. When the gage is raised through contact with a cheese, 10 the arm 721 is moved away from the lug 714^a. Consequently when the recess 717 is moved under the projection 716 by the cam 713, the spring 720 places the projection in said recess, thus locking the arms 709 and 15 711 together. In the continuing rotation of the cam 713, both arms are swung, thereby causing the arms 361 and 361^a to push the reserve thread out of the path of the knot-tying mechanism, and withdrawing the 20 latch 694 from the lug 696. When the switch block 686 reaches the plunger A of the unit containing the full cheese, said switch block yields to the pressure of the plunger, and the roller A' engages the side 691 of the plate 25 689 and is thereby moved laterally onto the dwell 685. Consequently the reserve bobbin is not placed in running position.

When the reserve thread is deflected out of the path of the knot-tying mechanism, the 30 projection 360 (Fig. 5) on the arm 361, which normally opens the clamp in which the end of the reserve thread is held, passes clear of the clamp.

It will thus be seen that when a full 35 cheese is met with, the reserve thread clamp is not opened, the reserve thread is deflected out of the path of the knotter, and the reserve bobbin remains in reserve position. When the winder-tending mechanism 40 has passed the unit, the operator removes the cheese.

I claim as my invention:

1. In a winder having a bobbin holder and a bobbin controlling plunger, winder-tending mechanism for actuating said plunger and having means rendering inoperative said plunger comprising a rock shaft, a reciprocating member, an arm operatively connected with said rock shaft to swing it, and 45 means controlled by the size of the yarn mass being formed by the winder for locking said arm to said member.

2. In a winder, the combination with a 50 bobbin holder having an operating element, winder-tending mechanism having a cam adapted to engage said element, and means for rendering said cam inoperative comprising deflecting means for said element, and means operable when the yarn mass being 55 formed by the winder has reached a predetermined size for rendering effective said deflecting means.

3. In a winder, the combination with a 60 bobbin holder having an operating element, 65 of winder-tending mechanism comprising a

cam normally adapted to engage said element to actuate it, and a switch on said cam operable when the yarn mass being formed by the winder has attained a predetermined size to prevent engagement of said element 70 by said cam.

4. In a winder, the combination with a bobbin holder having an operating plunger, of winder-tending mechanism having a cam normally adapted to engage said plunger to 75 operate it, a switch for deflecting said plunger from the cam when the yarn mass being formed by the winder has attained a predetermined size, said switch including a movable cam member, means normally holding said cam member in position to guide the plunger onto said cam, and means operable when the yarn mass attains a predetermined size to actuate said holding means so as to permit of a movement of the cam 80 member from its normal or guiding position.

5. In a winder, the combination with a bobbin-holder having a reciprocatory operating member, of means for actuating said 90 member including a traveling cam bar, said bar having a switch operable when the yarn mass being formed by the winder has reached a predetermined size to prevent said member from being engaged by said cam. 95

6. In a winder having a bobbin holder provided with a reciprocatory operating member, means for actuating said member including a bar having a cam surface and an offset dwell, and a switch operable when the 100 yarn mass being formed by the winder has acquired a predetermined size to deflect said member from its normal path on said cam surface onto said dwell.

7. In a winder, the combination with a 105 bobbin holder having a reciprocatory operating member, of means for actuating said member including a traveling bar having a cam surface, an offset dwell, and a switch for guiding said member in the travel of said bar either onto said cam surface or onto said dwell, said switch including a pivoted member, a latch normally operable to hold said pivoted member in position to guide the member onto the cam surface, a plate operable when the pivoted member is swung into inoperative position, to guide the member onto said dwell, and means for actuating the latch member when the yarn mass being 110 formed by the winder has reached a predetermined size. 115

8. A winder as set forth in claim 7, wherein the means for actuating the latch member comprises a rock shaft operatively connected to said latch, a pivoted arm operatively connected with the shaft to rock it, a reciprocating member, and means controlled by the size of the yarn mass for connecting said reciprocating member with said arm. 125

9. In a winder, the combination with a 130

bobbin holder having a bobbin controlling plunger, of winder-tending mechanism comprising a cam bar normally operable to actuate said plunger, said bar having a cam surface and an offset dwell, and switch means operable to guide the plunger either onto said dwell or said cam surface.

10. In a winder having a bobbin controlling element, a cam bar for actuating said element having a cam surface and an offset dwell, a guide member, means normally holding said guide member in position to guide said element onto said cam surface, and means for releasing said holding means whereby to cause the element to be guided onto said dwell.

11. The combination with a bobbin holder having an operating element, of actuating means for the element comprising a relatively movable bar having a cam surface, means for normally guiding said element onto said surface whereby to actuate the element, and means for rendering ineffective said guiding means whereby to prevent the actuation of said element.

12. In a winder, the combination with a bobbin holder having an operating element, of a relatively movable cam member normally operable to actuate said element and having a part operable to effect a lateral movement of said element whereby to prevent actuation of the element when the yarn mass being formed by the winder has attained a predetermined size.

13. In a winder, the combination of a bobbin holder having an operating element, means normally adapted to actuate said element comprising a relatively movable cam member having a movable part providing a portion of the cam surface, and means operable when the cheese being formed by the winder attains a predetermined size to permit a movement of said part by said element whereby to render the latter inoperative.

14. In a winder, the combination with a feeler for detecting when a cheese being formed by the winder has attained a predetermined size, of a movable part normally providing a cam surface, and means controlled by said feeler to permit a movement of said part to render it ineffective to actuate an element normally actuated thereby in the operation of the winder.

15. In a winder, the combination with means for detecting when a cheese being formed by the winder being wound attains a predetermined size, of an operating element and a relatively movable actuating member having a movable part adapted to provide a cam surface, and means controlled by said detecting means normally holding said part in operative position but permitting the movement thereof into inoperative

position when the cheese attains such predetermined size.

16. In a winder, the combination of a constantly rotating cam member, means normally operable to place a reserve bobbin in operative position including a latch member, and means operable by said cam member and controlled by the cheese being wound to actuate said latch member whereby to render said bobbin-placing means inoperative.

17. In a winder, the combination of means for supporting a reserve bobbin, means operable normally to move said bobbin into operative position including a cam block and a device normally holding it in operative position, a constantly reciprocating element, and means controlled by the size of a cheese being wound adapted for actuation by said reciprocating element to operate said holding device and render said cam block inoperative.

18. In a winder, the combination of means for supporting a reserve bobbin, cam means operable normally to move said bobbin into operative position and including a movable part, a constantly reciprocating element, means controlled by the size of a cheese being wound adapted for actuation by said reciprocating element to release said part for movement whereby to render said bobbin-placing means inoperative, and means operatively associated with the last mentioned means for moving a reserve thread out of operative relation with respect to a knotting mechanism.

19. In a winder, the combination of bobbin-holding means having a bobbin-discharging plunger, a constantly reciprocating member, means actuated by said member to render said plunger inoperative, and a device controlled by the size of the yarn mass being wound for rendering said reciprocating member operative to actuate the last mentioned means.

20. In a winder, the combination of means for holding a reserve bobbin, means including a plunger operable normally to effect the movement of said bobbin into running position, of means for rendering the bobbin moving means ineffective when a yarn mass being wound has attained a predetermined size including a constantly operating member, an oscillatory member, means under the control of the yarn mass for effecting a connection between said constantly operating member and said oscillatory member, and a device operatively associated with oscillatory member acting upon the movement of the latter to render said plunger inoperative.

21. A winder having, in combination, a bobbin-holder having an operating plunger capable of lateral movement, a cam for

depressing said plunger, and means for laterally moving said plunger out of the path of said cam.

22. A winder having, in combination, two arms arranged to swing upon a common axis, one above the other, a cam revolving upon an axis parallel to the first-mentioned axis, said cam engaging the lower arm, a

notched plate on the lower arm, a latch pivoted on the upper arm and adapted to engage the notch in said plate, and a cheese gage controlling said latch.

In testimony whereof, I have hereunto set my hand.

BURT A. PETERSON.
